(57) **CLAIM**

The ornamental design for a cooler, as shown and described.

DESCRIPTION

FIG. 1 is a top front right perspective view of a cooler showing my new design;

FIG. 2 is a top front right perspective view of the cooler shown in FIG. 1;

FIG. 3 is top front perspective view of the cooler shown in FIG. 1;

FIG. 4 is a top view of the cooler shown in FIG. 1;

FIG. 5 is a top front left perspective view of the cooler shown in FIG. 1;

FIG. 6 is a top rear right perspective view of the cooler shown in FIG. 1;

FIG. 7 is a top rear left perspective view of the cooler shown in FIG. 1; and,

FIG. 8 is a top rear perspective view of the cooler shown in FIG. 1.

The dashed broken lines show portions of the cooler and form no part of the claimed design.

1 Claim, 8 Drawing Sheets
